UNITED STATES PATENT OFFICE

2,575,592

HOLDER FOR ICE-CREAM CANS

William C. Kuykendall, Modesto, Calif.

Application September 8, 1948, Serial No. 48,231

2 Claims. (Cl. 220—15)

1

This invention is directed to, and it is an object to provide, a novel holder for ice cream cans disposed in a dispensing type, refrigerating cabinet; the holder being operative to prevent each can from turning when ice cream is being scooped therefrom.

Another object of the invention is to provide a holder for ice cream cans, as above, which comprises an expansion device engaged between the can on one side and an adjacent, surrounding member in the cabinet; said expansion device thus frictionally holding the can against turning motion.

A further object is to provide a holder for ice cream cans, as in the preceding paragraph, wherein the expansion device is an air inflated envelope of novel construction.

An additional object of the invention is to provide a novel insert assembly of can surrounding members for use in interiorly open cabinets which do not have can receiving cylinders therein. When a cabinet is fitted with can surrounding cylinders, the expansion devices frictionally engage between the cans and corresponding cylinders. In an initially interiorly open cabinet, the above insert assembly is used; the expansion devices then being engaged between the cans and surrounding rings which said assembly includes.

It is also an object of the invention to provide a holder for ice cream cans, which is adaptable for use—as an accessory—in conventional or existing type ice cream cabinets.

A further object of the invention is to provide a practical and reliable holder for ice cream cans, and one which will be exceedingly effective for the purpose for which it is designed.

These objects are accomplished by means of such structure and relative arrangement of parts as will fully appear by a perusal of the following specification and claims.

In the drawings:

Fig. 1 is a fragmentary sectional elevation of an ice cream cabinet, of cylinder type, showing the expansion device as used between the ice cream can and the cylinder.

Fig. 2 is an enlarged perspective view of one of the expansion devices, detached.

Fig. 3 is a fragmentary sectional elevation of an ice cream cabinet of initially interiorly open type; the cabinet being fitted with the insert assembly adapted for use with the expansion devices.

Fig. 4 is a fragmentary plan view showing one of the can surrounding rings of the insert assembly.

2

Referring now more particularly to the characters of reference on the drawings, and particularly to Figs. 1 and 2, the numeral 1 indicates an ice cream cabinet which includes a cylinder 2 having a top opening 3; the latter being adapted to be closed by a lid (not shown). The cylinder 2 extends from the top of the cabinet 1 downward to the bottom 4 thereof, and said cylinder 2 is adapted to receive an ice cream can 5 therein, with said can resting on the bottom 4.

The inside diameter of the cylinder 2 is slightly larger than the outside diameter of the can 5, whereby when said can is in place and rests on one side against the cylinder, there is a vertical space 6 between the opposite side of the can and the corresponding wall of said cylinder.

Normally when ice cream is scooped from the can 5, there is a tendency of the latter to rotate in the cylinder 1, which is both annoying and inconvenient. To prevent this turning of the can 5, the present invention provides the following:

The numeral 7 indicates a flexible and inflatable expansion envelope, which envelope is rectangular in elevation and somewhat elongated horizontally; such envelope also having a slight curve lengthwise to substantially match the curvature of the cylinder 2 and can 5 between which said envelope is engaged in the manner shown in Fig. 1.

The envelope 7 is disposed between the adjacent walls of the cylinder 2 and ice cream can 5 in the vertical space 6 at the lower end of the latter; i. e. at the lower end portion of the can.

The envelope 7 includes an inwardly projecting, upwardly opening hook 8 which engages the bottom edge flange 9 of the can 5 from below, whereby to prevent undesirable relative upward motion of the envelope 7.

A flexible hose 10 is connected to the upper edge of the envelope 7, intermediate its ends, and said hose extends upwardly in the vertical space 6 to a point above the can 5, and the hose is there fitted with a valve 11.

The device is initially assembled with the can 5 before its insertion in the cylinder 2; the envelope 7 then being deflated. After the can 5 is placed in the cylinder 2, a source of air pressure (not shown) is connected to the hose 10 at the valve unit 11, and the envelope 7 is inflated until it is tightly and frictionally wedged between said cylinder 2 and can 5. At this time the opposite side of the can bears directly against the cylinder 2.

When the envelope 7 is inflated, as above, it frictionally grips the can 5 to an extent such that

the can does not turn when ice cream is being scooped therefrom.

In certain types of ice cream cabinets there are no internal cylinders 2, and the cabinet is initially internally open. In order to adapt the present invention to this type of cabinet, the insert assembly shown in Figs. 3 and 4 is used, and which assembly comprises:

The ice cream cabinet is indicated at 12, having the usual top openings 13 for the placement of ice cream cans 14 in the cabinet in seated relation on the bottom 15 thereof. The openings 13 are normally closed by lids (not shown).

Below each opening 13, and in substantial alignment therewith, the bottom 15 of the cabinet 12 supports a can surrounded ring 16 whose internal diameter is slightly greater than the external diameter of the corresponding ice cream can 14, which can is surrounded, at its lower end portion, by said ring. Each ring 16 includes a plurality of circumferentially spaced, upstanding hold-down straps 17 having hooks 18 at their upper ends which releasably engage over the upper edge of the corresponding can 14.

Horizontal displacement of the rings 16 on the bottom 15 is prevented by horizontal tie straps 19 which connect between adjacent sides of the rings 16, and between said rings and adjacent walls 20 of the cabinet.

The horizontal tie straps 19 include depending hooks 21 at each end, which engage in eyes 22 on the sides of the rings 16, or on the walls 20. It is contemplated that each ring 16 will have four tie straps equally spaced thereabout, and extending radially outwardly to connect with the adjacent ring 16, or wall 20, as the case may be.

With the above described insert assembly, each ice cream can 14 is maintained in the cabinet 12 against any substantial lateral displacement. Then to prevent turning of each ice cream can 14 relative to the corresponding surrounding ring 16, an expansion envelope 23, of the type hereinbefore described in connection with Figs. 1 and 2, is engaged between each can 14 and the surrounding ring 16. Upon inflation of each expansion envelope 23 by means of its hose 24, there is an effective frictional locking of the can against turning.

The holder for ice cream cans in both of the above described embodiments provides a very practical and effective instrumentality for assuring against the inconvenient and annoying turn-

ing of ice cream cans in a cabinet during scooping of the ice cream for dispensing.

From the foregoing description it will be readily seen that there has been produced such a device as substantially fulfills the objects of the invention, as set forth herein.

While this specification sets forth in detail the present and preferred construction of the device, still in practice such deviations from such detail may be resorted to as do not form a departure from the spirit of the invention, as defined by the appended claims.

Having thus described the invention, the following is claimed as new and useful, and upon which Letters Patent are desired:

1. A holder for ice cream cans disposed in a cabinet, separate rings surrounding the can adjacent the lower ends thereof, the rings seating on the bottom of the cabinet, tie straps connecting the rings together, expansion devices engaged between the rings and cans and being effective to hold the latter in non-turning relation with respect to the rings, upstanding straps on the rings, and hooks on the upper end of the straps engaging over the upper edge of the cans.

2. A holder for ice cream cans disposed in a cabinet, separate rings surrounding the cans adjacent the lower ends thereof, the rings seating on the bottom of the cabinet, tie straps connecting the rings together, and air inflated envelopes engages between the rings and cans and being effective to hold the latter in non-turning relation with respect to the rings.

WILLIAM C. KUYKENDALL.
